UNITED STATES PATENT OFFICE.

LEONARD ADAMS, OF BUFFALO, NEW YORK.

TELESCOPING RADIO LOOP OR ANTENNA.

Application filed February 6, 1928. Serial No. 86,644.

My invention relates to radio antennæ or tuning devices for either the reception or transmission of radio signals, and my object is to provide a simple apparatus that can be adjustable and tunable to various wave lengths or radio frequencies by having the exact length or area of either inductive or transmissive surface.

I attain this object by the device shown in 10 the accompanying drawings in which—

Fig. 1, represents a perspective view of my telescoping radio loop or antennæ.

Fig. 2, shows the electric circuit.

Fig. 3, shows the telescoping element and 15 electric contact brushes.

Similar numerals refer to similar parts throughout the drawings.

This telescoping radio loop or antennæ consists of a suitable frame (1), in which 20 are suitably positioned insulated U or similar shaped members (2) which form one half, or a section, of a complete loop. The upright or extending segments of these U or similar shaped members (2) are hollow and 25 have at their ends suitable brushes (3). This section may also consist of a single straight member.

A secondary frame (4), in which are suitably positioned and insulated corresponding 30 U or similar shaped members (5) to suitably telescope the segments of the U or similar shaped members (2). This section may also consist of a single straight member to correspond to section above in such a manner so as to involve the telescoping principle.

The brushes (3) make an electric contact on each sliding or telescoping member (5). The U or similar shaped members 2 and 5 are to telescope into each other so as to make 40 a continuous multiple coil or loop and not a series of closed loops. However a single as well as a connected series of closed loops also the single as well as a number of straight members mentioned above if using the telescoping principle, are to be considered included in this application.

This apparatus may be made in various styles and shapes. Scales and gauges may be applied and a mechanism may be employed to operate the telescoping movement as may be desired.

What I claim and desire to secure by Letters Patent are:

1. A radio tuning device, comprising a 55 plurality of co-acting members, each provided with an insulated portion forming a

section of a loop, extending segmental portions of such members being so formed that when the members are brought into contact with each other, they will telescope each other, whereby the length of the loop thus formed may be varied as desired.

2. A radio tuning device, comprising a plurality of co-acting members, each provided with an insulated portion forming a section of a loop, the extending segmental portions of one of such members being hollow and the corresponding extending segmental portions of the co-acting member being solid, so that when the co-acting members are brought into contact with each other, they will telescope each other, whereby the length of the loop thus formed may be varied as desired.

3. A radio tuning device, comprising a plurality of co-acting members, each provided with an insulated portion forming a section of a loop, the extending segmental portions of one of such members being hollow and the corresponding extending segmental portions of the co-acting member being solid, and electric contact means mounted within the hollow extending segmental portion of one of the members, whereby the length of the loop thus formed may be varied as desired and an electric contact between the members may be assured.

4. A radio tuning device, comprising an insulated, transmissive unit, so shaped as to form a section of a loop, and a separate co-acting insulated, transmissive unit, so shaped that when the two units are in contact with each other, they will form a complete loop, the extending segmental portion of one of such units being hollow and adapted to receive the solid extending segmental portion of the other co-acting member, whereby the units may telescope each other and the length of the loop thus formed may be varied as desired.

5. A radio tuning device, comprising an insulated, transmissive unit so shaped as to form a section of a loop, and a separate insulated, transmissive unit so formed that when the two units are in contact with each other they will form a complete loop, the two units being provided with co-acting means for telescoping each other, whereby the length of the loop thus formed may be varied as desired.

6. A radio tuning device, comprising a plurality of insulated, transmissive units

2

forming a section of a loop, and a plurality of co-acting, insulated, transmissive units so formed that when the two units are in contact with each other, they will form a continuous multiple loop, the extending segmental portions of the two units being so formed that they will telescope each other when brought into contact, whereby the length of the loop thus formed by the contacting, co-acting units may be varied as desired.

7. A radio tuning device comprising a plurality of insulated, transmissive units forming a section of a loop, and a plurality of co-acting, insulated, transmissive units so formed that when the two units are in contact with each other they will form a continuous multiple loop, the segmental extending portions of one of the units being hollow, and the co-acting, extending segmental portions of the other unit being solid, and electric contact means so mounted in each of the extending segmental portions of one of the units that the co-acting solid extending segmental portion of the other unit will make an electric contact with each other, whereby the units will telescope each other and the length of the loop thus formed may be varied as desired.

into contact, they will telescope each other and a length of the loop thus formed may be varied as desired.

8. A radio tuning device comprising a plurality of insulated, transmissive units forming a section of a loop, and a plurality of co-acting, insulated, transmissive units so formed that when the two units are in contact with each other they will form a continuous multiple loop, the segmental extending portions of one of the units being hollow, and the co-acting, extending segmental portions of the other unit being solid, and electric contact means so mounted in each of the extending segmental portions of one of the units that the co-acting solid extending segmental portion of the other unit will make an electric contact with each other, whereby the units will telescope each other and the length of the loop thus formed may be varied as desired.

LEONARD ADAMS.
